FLORAL DISPLAY CART

Ralph W. Bachman and Dallas R. Humphrey, Minneapolis, Minn., assignors to Bachman's Inc., Minneapolis, Minn.

Filed Apr. 21, 1971, Ser. No. 136,288

Term of patent 14 years

Int. Cl. D12—02

U.S. Cl. D14—3

FIG. 2

FIG. 3

FIG. 1 is a perspective view taken from the front and one side of a floral display cart showing our new design;

FIG. 2 is an elevational view taken from the side opposite that shown in FIG. 1; and

FIG. 3 is a rear elevational view thereof.

We claim:

The ornamental design for a floral display cart, substantially as shown.
